COLLAPSIBLE COMBINED BABY CRIB AND PLAY PEN

Owen Blair Mitchell, La Center, Ky.

Application November 13, 1952, Serial No. 320,257

1 Claim. (Cl. 5—2)

This invention relates to a collapsible combined baby 15 crib and play pen.

An object of this invention is to provide a collapsible baby crib and play pen which is designed particularly for use in trailers so as to provide a simple and practical article which in its inoperative position will be disposed out of the way in a relatively small space.

Another object of this invention is to provide in a device of this kind a partially collapsible cabinet which forms the base for the crib and play pen when extended, and forms the front wall for the device when it is collapsed.

A still further object of this invention is to provide a portable or stationary combined crib and play pen which can be produced at small cost and which can be sturdily made so as to withstand relatively rough usage.

With the above and other objects in view, my invention consists in the arrangement, combination and details of construction disclosed in the drawings and specification, and then more particularly pointed out in the appended claim.

In the drawings—

Figure 1 is a plan view of a combined crib and play pen constructed according to an embodiment of this invention, showing the device in extended operative position.

Figure 2 is a detailed front elevation of the device in its extended operative position.

Figure 3 is a sectional view taken on the line 3—3 of Figure 2.

Figure 4 is a detailed front elevation of the device in its collapsed or inoperative position.

Figure 5 is a sectional view taken on the line 5—5 of Figure 4.

Figure 6 is a sectional view taken on the line 6—6 of Figure 5.

Figure 7 is a fragmentary sectional view taken on the line 7—7 of Figure 4.

Figure 8 is a fragmentary inner elevation of the upper front portion of the crib and play pen.

Figure 9 is a fragmentary sectional view showing the guide for the lower or rear portion of the bed or crib.

Figure 10 is a fragmentary sectional view showing the guide track for the lower portion of the front movable panel.

Figure 11 is a fragmentary sectional view taken on the line 11—11 of Figure 3.

Figure 12 is a fragmentary sectional view taken on the line 12—12 of Figure 11.

Figure 13 is a fragmentary front elevation showing the detachable securing means for the mattress.

Figure 14 is a fragmentary sectional view taken on the line 14—14 of Figure 6.

Figure 15 is a fragmentary side elevation of one of the panel locking means.

Figure 16 is a fragmentary sectional view taken on the line 16—16 of Figure 2.

Referring to the drawings, the numeral 20 designates

2

generally a cabinet or housing which is formed of an inner vertical wall 21, a bottom wall 22, and a top wall 23. The cabinet 20 also includes opposite end walls 24 and a two part front wall generally indicated at 25, which 5 is formed of a lower panel 26 and an upper panel 27. The two panels 26 and 27 are hinged together by hinge members 28 and lower panel 26 is hinged as at 29 to the stationary bottom wall 22 of cabinet 20.

The inner side of upper panel 27 is provided with gliders or casters 30 which are adapted to engage a plane surface when panel 27 is collapsed or swung beneath panel 26, as shown in Figure 3, and the crib and play pen are extended. Panel 27 forms, with panel 26, the extended base of the cabinet 20.

A play pen generally indicated at 31 is hingedly secured as at 32 to the end walls 24 of cabinet 20, and play pen 31 is formed of hingedly connected together end members 33 and 34 which are hinged as at 35, and are adapted to be locked in aligned extended position by means of a locking bar 36 engaging a bolt or headed fastening member 37. The end members 33 and 34 are each formed of an upper bar 38, a lower bar 39, and dowels 40 which are connected between the upper and lower bars 38 and 39.

25 The play pen is also formed of a two part front wall generally indicated at 41, and front wall 41 is formed of a collapsible upper wall 42 and a stationary bottom wall 43. The wall 42 is formed of an upper horizontal bar 44, a lower horizontal bar 45, and spaced dowels 46 secured between the bars 44 and 45. Lower wall 43 is formed of an upper bar 47, a lower bar 48, and connecting dowels 49. Lower wall 43 has fixed to the bars 47 and 48 upstanding corner posts 50, and each corner post 50 is provided with a lower vertically disposed guide channel 51 which terminates at its upper end in a horizontal channel 52, and a depending locking channel 53. Each corner post 50 is also formed with an upper vertically disposed channel 54 which at its upper end communicates with an upwardly and inwardly inclined channel 55, and channel 55, as shown in Figure 8, communicates with an upper vertical channel 56 which is parallel with channel 54 and inwardly offset therefrom.

Locking channel 53 is disposed in vertical alignment with upper channel 56 and lower bar 45 has extending from the opposite ends thereof slide pins 57 which engage in channels 51, 52, and 53. Upper bar 44 is provided at each end thereof with slide pins 58 which engage in channels 54, 55, and 56.

When upper wall 42 is in its extended elevated position, lower bar 45 will be disposed in overlying and contacting position with respect to upper bar 47 of lower wall 43. The two bars 45 and 47 may be locked together by means of a hook or locking member 59 engaging a headed screw or keeper 60 which is carried by the upper bar 47 of lower wall 43.

55 A crib floor panel 61 is hingedly secured as at 62 to an inner bottom wall 63 disposed in upwardly offset relation with respect to bottom wall 22, and floor panel 61 when in collapsed or inoperative position is adapted to be locked between the end walls 24 by means of spring-pressed locking means 64, as shown in Figure 14. Bottom member 61 is adapted when the crib and play pen are extended to be swung downwardly to a horizontal position with the outer or forward edges thereof resting on a shoulder or ledge 65 which is formed at the inner side 60 of bottom bar or rail 48, as shown in Figure 5.

A bed supporting panel 66 is movably disposed between the end walls 24 and the latter are formed at their inner sides with an upwardly and outwardly inclined guide channel 67 within which slide pins 68 carried by the opposite ends of panel 66 are adapted to slidably engage. The guide channel 67 is formed at its upper outer end

with a keeper recess 69 within which the pin 68 is adapted to engage so that the mattress or bed supporting panel 66 will be held against collapsing under the weight of a child resting on the mattress 70 which is secured by snap fasteners 71 or the like to the panel 66.

Upper rail or bar 47 is formed at its inner side with a ledge or shoulder 72 upon which the forward edge of the panel 66 is adapted to rest for supporting panel 66 and mattress 70 in a horizontally extended or operative position. Panel 66 is held in a vertical inoperative position within the cabinet 20 by spring-pressed locking means 73 which are identical with the locking means 64, shown in Figure 14.

A drawer 74 is slidably mounted on angle members 75 which are secured to the end walls 24 at a point above the top of the crib and play pen structure and provides a means whereby articles may be placed in the upper portion of the cabinet for use with the play pen and crib. It will, of course, be understood that there may be as many drawers 74 as may be desired.

In the use and operation of this structure the cabinet 20 where used in a trailer, is adapted to have the rear wall 21 secured to a wall or other support in the trailer. When the device is not in use the crib and play pen is collapsed after the manner shown in Figure 5. If it is desired to use the play pen, panels 27 and 26 are swung downwardly with panel 27 disposed beneath panel 26 in the horizontal position of the latter, as shown in Figure 3. The play pen may then be pulled outwardly so as to rest on horizontal panel 26, and bottom panel 61 may then be swung downwardly to engage the shoulder or ledge 65 of rail 48.

When the device is used as a play pen, movable wall 42 is raised upwardly to be disposed in alignment with bottom wall 43, as shown in Figures 2 and 3. If the device is to be used as a crib, the mattress supporting member 66 is pulled outwardly to a horizontal position with supporting studs or pins 68 engaging in the keeper notches 69, and the outer edge of panel 66 resting on supporting shoulder or ledge 72. If desired, the upper front wall member 42 may be dropped downwardly in front of lower wall 43 by lifting upper wall 42 upwardly a short distance to move the lower pins 57 out of locking channel 53 and then moving the wall 42 outwardly through channel 52 into channel 51. Upper wall 42 may then be dropped downwardly in front of lower wall 43.

This device will provide a very compact combined crib and play pen which may be disposed in a house or may be disposed in a stationary position in a trailer. The device may be sturdily made and will withstand relatively

50

134,751

rough usage and can be produced at a relatively small cost.

I do not mean to confine myself to the exact details of construction herein disclosed, but claim all variations 5 falling within the purview of the appended claim.

What I claim is:

A combined cabinet, crib and play pen comprising a cabinet formed of a rear wall, opposite end walls each having an inclined guide channel therein, said channels being in opposed aligned parallel relation, a top wall, a bottom wall, and a front wall formed of upper and lower hinged together panels, means hingedly securing said lower panel to said bottom wall, said upper panel being swingable beneath said lower panel when the latter is swung downwardly to a horizontal extended position, a pair of opposite end pen walls hinged to said cabinet end walls, each end pen wall being formed of a pair of hingedly connected together members, a front pen wall formed of a lower member, vertical posts carried by said 10 lower member, means hingedly securing the forward member of each of said end pen walls to each of said posts, each of said posts having upper and lower guide channels on the inner sides thereof, said front pen wall also including an upper wall, upper and lower pins carried by said upper wall slidably engaging in said channels in the posts, the lower channel of each post terminating in a horizontal inwardly extending channel and each horizontal channel terminating at its inner end in a depending locking channel, an inner bottom carried by said cabinet, a pen bottom hinged to said inner bottom, means carried by said cabinet releasably holding said pen bottom in vertical collapsed position, an inner front panel carried in said cabinet, connections between the edges of said inner front panel and said channels in opposite end 15 walls, a mattress carried by said inner front panel, means including said last mentioned channels and said connections for moving said inner front panel and mattress to horizontal position exteriorly of said cabinet, and means securing said inner front panel and said mattress 20 in horizontal position.
